(57) **CLAIM**

The ornamental design for a leash for fidget device, as shown and described.

DESCRIPTION

FIG. 1 is a top perspective view of the leash for fidget device according to the present invention;

FIG. 2 is another top perspective view thereof;

FIG. 3 is a top view thereof;

FIG. 4 is a bottom view thereof;

FIG. 5 is a front view thereof;

FIG. 6 is a bottom view thereof;

FIG. 7 is a left side view thereof, the right side view being a mirror image of the left side view;

FIG. 8 is a cross-sectional view thereof taken in the direction of line 8-8 in FIG. 3; and,

FIG. 9 is a cross-sectional view thereof taken in the direction of line 9-9 in FIG. 3.

The broken lines shown in the figures depict portions of the leash for fidget device that form no part of the claimed design.

1 Claim, 6 Drawing Sheets
